Primary Examiner — Philip S Hyder(74) Attorney, Agent, or Firm — Jason H. Foster; Kremblas & Foster(57) CLAIM

The ornamental design for a fitness machine, as shown and described.

DESCRIPTION

FIG. 1 is a front view of a fitness machine showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front right upper perspective view thereof; and,

FIG. 8 is a front right lower perspective view thereof.

The broken lines depict portions of the fitness machine in which the design is embodied that are not considered part of the claimed design.
